UNITED STATES PATENT OFFICE

OTTO WULFF AND ROBERT SEDLMAYR, OF MUNICH, AND WILHELM ECKERT, OF HOCHST-ON-THE-MAIN, GERMANY, ASSIGNORS TO GENERAL ANILINE WORKS, INC., OF NEW YORK, N. Y., A CORPORATION OF DELAWARE

AROMATIC DIACIDYL COMPOUND AND PROCESS FOR PREPARING THE SAME

No Drawing. Application filed October 18, 1927, Serial No. 227,050, and in Germany October 23, 1928.

The present invention relates to diacidyl derivatives of the naphthalene and acenaphthene series and a process for preparing the same.

5 The preparation of diacidyl hydrocarbons of the naphthalene and acenaphthene series, for instance of the 1,5-dibenzoylnaphthalene, could hitherto be carried out only by way of a number of intermediate products and in 10 a manner not practicable for technical purposes.

We have now found that the diacidyl hydrocarbons of the naphthalene and acenaphthene series can be obtained by causing 15 the aromatic compounds of the following general formula:

20

wherein X and Y stand for two hydrogen atoms or for the group

25

and R for hydrogen or a CO-alkyl group or CO aryl group and any aromatic or aliphatic acid chloride to act upon each other in the 30 presence of aluminium chloride, with or without the use of a diluent, and, in case the R stands for hydrogen, by subjecting the hydrocarbons first to the action of an acid chloride at about 0° C. and then the action of 35 a further quantity of an acid chloride at a temperature of about 30° C. to 100° C. in the presence of aluminium chloride.

Diacidyl-hydrocarbons are already per se known, for instance those of nesitylene, an- 40 thracene, phenanthrene; however, in view of the peculiar manner in which the aluminium chloride acts, no conclusion can be drawn as to whether the naphthalene and acenaphthene would behave in an analogous manner. Generally, the hydrocarbons which are 45 already acidylated, react with acid chlorides only with great difficulty. It is known that for this reason it is possible to effect the mono-acidylation with a good yield. More- 50 over it was to be presumed that when trying

to carry out the diacidylation by means of aluminium chloride, the latter would have another action, for instance a condensing-action upon the monoacidyl compound and would thus at least diminish the yield of diacidyl hydrocarbons if not render it quite insignificant. Diacetyl-acenaphthene is already known, however it has been isolated only as a by-product and in a very trifling quantity from the high boiling portions of the reaction product obtained in the manufacture of 55 5-acetyl-acenaphthene. Therefore, diacetyl-acenaphthene cannot be industrially prepared in this way. It is only by our present invention that a practical way has been found to prepare the diacetyl-acenaphthene 60 with a good yield.

Our new process may, for instance be carried out in such a manner that there is used as parent material either a mixture of aluminium chloride and ready-made monoacidyl-hydrocarbon or the crude aluminium chloride-monoketo compounds produced in the manufacture of monoacidyl-hydrocarbons from a hydrocarbon, an acid chloride and aluminiumchloride, either directly or if preferred after separating the solvent. A third way to carry out the new process is to start from the respective hydrocarbons and to proceed in the manner set forth in the 70 following examples.

The diacidyl-hydrocarbons of the naphthalene and acenaphthene are of considerable technical interest as being valuable intermediate products for the manufacture of vat 85 dyestuffs.

The following examples serve to illustrate our invention but they are not intended to limit it thereto, all parts being parts by weight.

(1) 23 grams of α -benzoylnaphthalene are mixed with 16 grams of benzoyl chloride and there are then cautiously added 15 grams of aluminium chloride at about 30° C. to 35° C. There are then added in the course of one 95 hour another quantity of 21 grams of aluminium chloride while well stirring, during which operation the temperature is gradually raised from 45° C. to 90° C. and finally kept for another half hour at 100° C. During the 100

reaction hydrochloric acid escapes with effervescence. The dark brown melt thus obtained is decomposed with water, separated from the aqueous portion, washed first with diluted caustic soda solution and then with water. After having allowed the product to dry it is recrystallized from boiling benzene. In the cold the pure 1,5-dibenzoylnaphthalene of the melting point 186.5° C. separates in crystalline form. From the mother liquor a further quantity of 1,5-dibenzoylnaphthalene can be extracted and also isomerides which are readily soluble in benzene and can be isolated by means of alcohol or vacuum distillation from any secondary condensation products (having a melting point of about 300° C. under 12 mm. pressure).

The yield of 1,5-dibenzoylnaphthalene amounts to approximately 60 per cent of the 20 isomeric (presumably 1,8-) dibenzoylnaphthalene to about 20 per cent of the theory.

(2) 26 grams of 5-benzoylacenaphthene are subjected to reaction as indicated in Example 1, keeping however the temperature 25 generally somewhat lower, finally at about 70° C. and while taking care that the mass is well and vigorously stirred, because the melt tends to become very viscous and stiff. The reaction may also be performed in a solution 30 of carbon disulfide. The resulting crude product, after being decomposed with water or the like and dried, is purified by recrystallization from alcohol or extraction with ether, there being left undissolved a 35 considerable quantity of a dark secondary condensation product. The dibenzoylacenaphthene crystallizes from the solvent in nice crystals having a melting point of 143° C. From the mother liquors can be obtained 40 a further quantity of the product as well as unaltered monoketone. The yield amounts to about 50 per cent.

(3) 19.5 grams of 5-acetylacenaphthene are mixed and stirred with a small quantity 45 of carbon disulfide and to this mixture are slowly added 15 grams of aluminium chloride, whereupon the orange-colored aluminium-chloride compound separates in the form of a magma. There is then added by drops in 50 the course of about 3/4 hour, while very well stirring, a concentrated solution in carbon disulfide of the compound obtained from 12 grams of acetyl chloride and 14 grams of aluminium chloride, during which operation the 55 temperature is kept at 30° C. to 35° C. and much hydrochloric acid escapes. There are then furthermore slowly added 6 grams of aluminium chloride, the resulting dark, thick mass is thoroughly stirred and finally the 60 temperature is raised until the carbon disulfide begins to boil. The product is then decomposed with water, the carbon disulfide is blown off by means of steam and the product of the reaction, after it has cooled, is separated, washed and dried. It is then dis-

solved in hot alcohol and any residue left is filtered off. After cooling, the diacetyl acenaphthene crystallizes in beautiful crystals which melt at 146° C. A further quantity of the principal substance can be obtained from the mother liquor by concentration and a portion of unaltered 5-acetyl acenaphthene by vacuum distillation or by crystallization. The yield of diacetylacenaphthene amounts to 70-80 per cent of the converted 5-acetyl-acenaphthene.

(4) 128 parts of naphthalene are suspended in 128 parts of benzoyl chloride at 0° C. and to this mixture are added by portions 200 grams of aluminium chloride, care being taken that the temperature does not exceed 0° C. The mass is kept at a temperature of 0° C. until the evolution of hydrochloric acid has ceased; there are then again added 160 grams of benzoyl chloride; the whole is 80 heated to 30°-40° C. and at this temperature 150 grams of aluminium chloride are added in portions. When all of the aluminium chloride has been introduced, the mass is heated to 90° C. there are again added 200 grams of aluminium chloride and the whole 90 heated for one hour to 100° C. The final product, after being decomposed with water and distilled by means of steam yield when recrystallized from glacial acetic 1,5-di-95 benzoylnaphthalene with a yield of 70 per cent.

(5) Into a mixture of 46 parts of acenaphthene and 99 parts of mono-chloracetyl-chloride in 400 parts of carbon disulfide are 100 introduced, while externally cooling, 110 parts of aluminium chloride care being taken by cooling that the solvent does not become heated by the reaction-heat to the boiling point. After all of the aluminium chloride has been introduced the mass is allowed to stand for a rather long time (preferably for about 24 hours) while cooling and it is then heated for about one hour on the steam bath. After decomposition with ice followed by 105 distillation with steam to remove the carbon disulfide, the residue is recrystallized from glacial acetic acid. The so obtained hitherto unknown dichloroacetylacenaphthene which has probably the following formula:

shows the form of large almost colorless needles, melting at 194° C. to 195° C. In this manner the said compound is obtained by a single operation and with a yield of about 70 per cent.

(6) If instead of the chloracetyl chloride according to Example 5, acetyl chloride is used and the operations carried out with the

same quantities as indicated in this example, there is obtained after purification and reprecipitation of the crude product from alcohol, the di-acetyl-acenaphthene in colorless 5 prisms melting at 146° C.

We claim:

1. The process of preparing an aromatic diacidyl compound which comprises causing a compound of the following general formula:

15

wherein X and Y stand for hydrogen or jointly for the group H_2C-CH_2 and R represents hydrogen, CO-alkyl or CO-aryl, to react with an acid chloride in the presence of aluminium chloride.

2. The process of preparing an aromatic diacidyl compound which comprises causing a compound of the following general formula:

30

wherein X and Y stand for hydrogen or jointly for the group H_2C-CH_2 to react with an acid chloride, first with a quantity at about 0° C. and then with a further quantity at a temperature of about 30° C. to 100° C., in the presence of aluminium chloride.

3. The process of preparing an aromatic diacidyl compound which comprises causing a compound of the following general formula:

45

wherein X and Y stand for hydrogen or jointly for the group H_2C-CH_2 , and R represents hydrogen, CO-alkyl or CO-aryl, to react with benzoyl chloride in the presence of aluminium chloride.

4. The process of preparing an aromatic diacidyl compound which comprises causing a compound of the following general formula:

60

65 wherein X and Y stand for hydrogen or

jointly for the group H_2C-CH_2 to react

with benzoyl chloride, first with a quantity at about 0° C. and then with a further quantity at a temperature of about 30° to 100° C., 70 in the presence of aluminium chloride.

5. The process of preparing an aromatic diacidyl compound which comprises causing a compound of the following general formula:

75

wherein R stands for hydrogen, CO-alkyl or CO-aryl to react with an acid chloride in the presence of aluminium chloride.

6. The process of preparing an aromatic diacidyl compound which comprises causing naphthalene to react with an acid chloride, first with a quantity at about 0° C. and then with a further quantity at a temperature of about 30° C. to 100° C. in the presence of aluminium chloride.

85

7. The process of preparing an aromatic diacidyl compound which comprises causing a compound of the following general formula:

90

95

wherein R stands for hydrogen, CO-alkyl or CO-aryl to react with benzoyl chloride in the presence of aluminium chloride.

100

8. The process of preparing an aromatic diacidyl compound which comprises causing naphthalene to react with benzoyl chloride, first with a quantity at about 0° C. and then with a further quantity at a temperature of about 30° C. to 100° C., in the presence of aluminium chloride.
